UNITED STATES PATENT OFFICE.

JOHN LLOYD WILLIAMS AND THOMAS HENRY WILLIAMS, OF SHENANDOAH, PENNSYLVANIA.

COAL OR ROCK DRILL.

SPECIFICATION forming part of Letters Patent No. 408,867, dated August 13, 1889.

Application filed April 27, 1889. Serial No. 308,871. (No model.)

To all whom it may concern:

Be it known that we, JOHN LLOYD WILLIAMS and THOMAS HENRY WILLIAMS, both of Shenandoah, Schuylkill county, State of Pennsylvania, citizens of the United States, have invented certain new and useful Improvements in Coal or Rock Drills, of which the following is a full, clear, and exact description, reference being had to the accompanying drawings, forming part of this specification, and in which—

Figure 1 is a side elevation of a drill containing our invention. Fig. 2 is a vertical central section of the operative parts on line $\alpha\alpha$ of Fig. 1. Fig. 3 is a front elevation of said operative parts. Fig. 4 is a lateral cross-section on line $z z$, Fig. 1; and Fig. 5 is a plan of the gear which is feathered to and operates to rotate the drill-spindle, shown in cross-section, and the drill-tool carried thereby.

Our present invention relates to certain improvements upon the coal or rock drill for which Letters Patent No. 357,748 were granted to John Lloyd Williams on February 15, 1887; and our invention consists in the several parts and devices of a drilling-machine and their combinations therein, hereinafter particularly described, and as more particularly recited in the claims.

A is the stock or supporting-bar of the drill, having at its free end the series of teeth shown, to be forced to and held against the side of a recess cut in the bed of coal or rock, as shown, by means of a wedge A', pivotally jointed to and carried by a brace-rod A², the opposite end of said rod being detachably and adjustably seated in a slot in a lug A³, near the upper end of said bar, by means of jam-nuts, as shown, working above and below said lug on a threaded portion of the rod. The drill-operating mechanism, supported by the bar and brace-rod, is thus mounted in position for drilling. These described devices constitute a part of the invention set forth in the Letters Patent hereinbefore referred to.

We mount the drill-operating mechanism upon the supporting-bar by means of a screw-bolt A⁴, which passes through a suitable aperture a in the upper end of the bar to and into a threaded aperture or recess b in the

frame B of said drill mechanism, so that the bar is thus united pivotally to the frame at this point; and we provide a bolt A⁵ set in lug-piece A³, which bolt reaches through an aperture in and pivotally unites said lug to the bar A, and which bolt is adapted in length to extend through a laterally-extending slot b' in a lug b² on said frame B. By means of these devices the drill-frame B is given a lateral adjustment on the supporting-bar, and the brace-rod is given a similar adjustment on said rod, while the parts are held rigidly and effectively in their adjusted positions by means of the screw-bolt A⁴ and a nut a', working to the face of the lug b² on the threaded end of the bolt A⁵. The degree of adjustability of the frame B on the rod A by means of the described devices depends upon the length of the slot b' in the lug b² on the frame, and when this slot is given considerable length it may be preferably curved somewhat for obvious reasons, as shown.

We find that by the means described the effective and useful adjustment of the drill-frame on the supporting-bar for the purposes intended is secured, and a desirable adjustability of the rod A² on said bar is obtained.

C is the combined drill-spindle and feed-screw, having a chuck c at its lower end for attaching the drill-tool C' and threaded throughout its length, as shown. The screw C has bearings in plane-faced boxes D D' on the frame B, in which it is rotatable to effect the rotation of the tool C' in drilling.

E is the feed-nut, which is internally threaded to correspond to the thread on spindle C, and which is seated in one of the boxes, preferably the upper one D, upon and interposed between said spindle C and said box, as shown. The nut E is provided with the hand-wheel E', and it also preferably has the external annular groove e, constituting its bearing in its box, and by which it is held from longitudinal displacement therein. The box D affords a loose bearing for the nut E, which is preferably accomplished by hinging the upper half d to the lower half d', which is carried by and may be integral with the frame B, as shown, and holding the two halves together by a pin d², passed through a staple d³, which is fixed in the lower half and ex-

tends through and above a slot d^1 in the free end of the upper half, as shown. A circular leaf-spring d^5 is desirably placed about the nut E within its groove-bearing e , and thus 5 interposed between the nut and the box-surfaces and operating to force the box sections apart, and thus ease the bearing on the nut. A set-screw E^2 works in an aperture in the box, and is adapted to impinge upon the nut 10 E or its encircling spring, and thus force the nut tightly against the opposite box-face and hold it more or less rigidly in the box, depending upon the extent to which said set-screw is turned down upon the nut.

15 It is evident that by means of the described devices, when the spindle C is being rotated in operating the drill-tool, the feed-nut may be permitted to rotate with said spindle by loosening the set-screw E^2 and allowing the 20 nut to turn freely in the box D, while at the same time the operator may readily and conveniently control the feed by grasping the hand-wheel E' at any time and holding it still or rotating it in its bearing, when the rotation of the spindle C as it operates the drill will cause it to feed forward on its threaded bearing in the nut; or the set-screw may be turned down hard and the spindle will feed continuously during its rotation a distance 25 equal to the full pitch of the thread on the same and feed-nut; or the set-screw may be somewhat tightened, and while the nut when not manipulated may still rotate with spindle C, yet when grasped by the operator by 30 its hand-wheel the feed may be controlled by the operator and effected to more or less of the pitch of the thread on the spindle.

We find it preferable to construct both the boxes D and D' with their upper halves 40 hinged, as described, and to form the pin d^3 of such a length that it will be common to both boxes in fastening the upper halves thereof by the described staples. The pin d^3 is desirably fastened to the frame by a chain 45 d^6 , as shown. By these means the spindle and its operating mechanism may be readily unseated and replaced in the boxes.

To effect the rotation of the spindle C, we 50 preferably employ a spur-gear c' , which is mounted thereon within the frame B between the boxes D D', and which has a hub c^2 reaching to and abutting against the lower face of the feed-nut, as shown. The gear c' has a feather or feathers c^3 , which take in a groove 55 or grooves c^4 , extending longitudinally of the spindle, so that while the rotation of the gear operates to rotate the spindle the spindle may move freely through the gear as it is fed forward or backward. The gear c' is driven by 60 a pinion c^5 on a shaft c^6 , having bearings in the frame B and operated by cranks c^7 on its outer ends.

The feed-nut E and its hand-wheel may be 65 split into sections longitudinally, as shown. When mounted upon the bar C in the box D, these sections will be held together by the box and set-screw E^2 , and when it is desired

to run the spindle backward to remove the drill-tool from its hole in the coal or rock, or to change the tool, by entirely loosening the 70 sectional nut in its seat in the box, the thread on the sections may be wholly disengaged thereby from the thread on the spindle and the spindle be drawn backward freely through the nut without rotation.

75 What we claim as our invention, and desire to secure by Letters Patent, is—

1. In a drilling-machine, the combination, with the frame carrying the drill-operating mechanism and provided at one end with a 80 lug having therein a long lateral slot, of a supporting-bar pivotally bolted to said frame at the opposite end thereof, a lug-piece provided with a bolt extending through said bar and the said lateral slot in the frame, a nut 85 on said bolt to hold the same in said slot, a brace-rod seated at one end in said lug-piece, and a wedge carried by said rod at its opposite end, substantially as and for the purpose set forth.

90 2. In a drilling-machine, the combination, with the supporting-bar and frame carried thereby, of a rotatable drill-spindle externally threaded throughout its length and having bearings in boxes on said frame, and a feed-nut on said threaded spindle at and having 95 loose bearing in one of said boxes, together with a set-screw working in said box and adapted to impinge upon said nut at its bearing 100 therein, substantially as and for the purpose set forth.

3. In a drilling-machine, the combination, with the supporting-bar and frame carried thereby, of a rotatable drill-spindle externally threaded throughout its length and having 105 bearings in boxes on said frame, a feed-nut on said threaded spindle at one of said boxes, and provided with an external circumferential groove at which it has bearing around 110 said spindle in said box, a loose tap or section 110 of said box, a leaf-spring on said nut in said bearing-groove therein, and a set-screw working in said loose box and adapted to impinge 115 upon said spring and nut at its bearing therein, substantially as and for the purpose set forth.

120 4. In a drilling-machine, the combination, with the supporting-bar and frame carried thereby, of a rotatable drill-spindle externally threaded throughout its length and having 120 bearings in boxes on said frame, a feed-nut composed of longitudinal sections mounted on said threaded spindle at one of said boxes, and provided with an external circumferential groove at which it has bearing around 125 said spindle in said box, a loose tap or section of said box, and a set-screw working in said loose box and adapted to impinge upon said nut at its bearing therein, substantially as and for the purpose set forth.

130 5. In a drilling-machine, the combination, with the supporting-bar and frame carried thereby, of a rotatable drill-spindle externally threaded throughout its length, a feed-nut on

said threaded spindle, provided with an external circumferential groove, boxes on said frame in which said spindle and its feed-nut have bearings, each said box having a section 5 thereof fixed on said frame and a section hinged at one end and detachably attachable at its opposite end to said fixed section, and a set-screw working in the box in which said feed-nut has bearing and adapted to impinge 10 upon said nut therein, substantially as and for the purpose set forth.

6. In a drilling-machine, the combination, with the supporting-bar and frame carried thereby, of a drill-spindle externally threaded 15 throughout its length and provided with an external longitudinally-extended groove or grooves, a feed-nut on said spindle, provided

with an external circumferential groove, boxes on said frame in which said spindle and its nut have the described bearings, a set-screw working in the box, in which said nut has bearing, and adapted to impinge thereon 20 therein, a gear on said spindle and feathered to said groove or grooves therein, and a pinion engaging said gear and mounted on a 25 shaft having bearings in said frame and provided with actuating-cranks, substantially as and for the purpose set forth.
